UNITED STATES PATENT OFFICE.

ARTHUR MELLOR, OF NEW BEDFORD, MASSACHUSETTS, ASSIGNOR OF ONE-HALF TO
DENIS FARRON MELLOR, OF NEW BEDFORD, MASSACHUSETTS.

TENSIONING DEVICE FOR LOOM SHUTTLES.

Application filed August 7, 1924. Serial No. 730,657.

To all whom it may concern:

Be it known that I, ARTHUR MELLOR, a citizen of the United States, residing at New Bedford, in the county of Bristol and State of Massachusetts, have invented certain new and useful Improvements in Tensioning Devices for Loom Shuttles, of which the following is a specification, reference being had to the accompanying drawings.

10 This invention relates to tensioning devices for loom shuttles, and particularly to certain improvements in the tensioning device disclosed in my Patent #1,493,366, granted on May 6, 1924, this patent showing 15 a tensioning device which consists of opposed members having interior, upwardly opening, vitreous ribs, the ribs of one member fitting into or between the ribs of the other member, and a thread passing between 20 and contacting with these vitreous ribs.

One of the objects of the present invention is to improve upon the construction illustrated in my prior patent by the provision of improved means whereby the two 25 members may be adjusted toward or from each other to adapt the device to coarser or finer yarns.

A further object is to provide a tensioning device of this character which is simpler to 30 adjust than the tensioning device illustrated in my prior patent and which will lessen the danger of the screws coming loose and damaging the reed, the device being further so constructed that the tensioning members 35 may be made smaller so as to fit any shuttle either for bobbin or cop filing.

Other objects will appear in the course of the following description.

My invention is illustrated in the accompanying drawings, wherein:—

Figure 1 is a fragmentary top plan view of a shuttle constructed in accordance with my invention;

Figure 2 is a horizontal section on an enlarged scale;

Figure 3 is a section on the line 3—3 of Figure 2;

Figure 4 is a perspective view of one of the tensioning members;

Figure 5 is a perspective view of the other tensioning member.

Referring to these figures, 10 designates a shuttle of ordinary construction and having the usual kerf 11 which extends forwardly and transversely and connects with

the horizontal kerf 12 which in turn communicates with a porcelain eye 13. The bobbin of the shuttle is mounted, of course, upon the longitudinally extending shaft 14. This construction is the standard construction and requires no further description. 60

Disposed within the shuttle and against each side wall thereof are the metal plates or blocks 15 and 16 which are preferably cast. The block 15 at its lower end is formed 65 with an angularly disposed base or flange 17 formed upon its upper face with three sockets 18, and the upper portion of the plate is formed with three outwardly projecting flanges 19, the under faces of which 70 are also formed with sockets. At the junction of the vertical portion of the plate 15 with the base 17 there is a longitudinally extending groove 20. The upper sockets and the lower sockets constitute a holder for 75 three cylindrical rods 21 of glass. The lower sockets are open at their lower ends to permit the insertion of these glass rods and then this face may be filled with any suitable initially plastic filling material designated 80 at 22.

The base 17 has a transversely extending slot 23 extending inward from the inner edge of this base or flange 17 and adjacent one end of the plate or block 15, and passing 85 through the other end of the plate or block 15 is a bolt 24 having a head 25 engaging against the wall of the shuttle 10 and passing through the adjacent wall of the shuttle and engaged therewith by means of a nut 90 26 which is, of course, designed to be disposed within a countersink 27 in the shuttle wall. The plate 16 is similar to the plate 15 except that it has no base or flange 17 and in place of having three sockets for the 95 reception of three glass rods 21 it has sockets for the reception of two glass rods 21^a, and these plates 15 and 16 are so disposed that the two glass rods of the plate 16 are disposed opposite to the spaces between the 100 three glass rods of the plate 15, as illustrated in Figure 2, so that the yarn passing from the bobbin is obliged to take a more or less sinuous course in contact alternately with each glass rod until the thread passes out through the eye 28. Thus the thread comes in contact with all five of these glass rods which gives the proper tension upon the 105 thread.

The plate 16 also differs from the plate 110

15 in that it is provided adjacent one end with a downwardly extending screw 29 having a head, the shank of the screw being engageable in the slot 23 of the plate 15. Thus 5 the plate 16 may be adjusted toward or from the plate 15 and held locked in its adjusted position by turning up on the screw 29. The plate 16 is also provided in its lower end with outwardly projecting portions 30 10 within which these sockets for the lower glass rods are formed. At the entrance end of the plate 16 there is provided a guide wire 31, the upper end of which is inserted in a hole in the plate 16. This guide wire 15 extends downward and inward and also toward the shuttle cavity. The thread from the shuttle passes beneath this guide wire and this guide wire acts to prevent the thread from ballooning. It will be seen that 20 this finger or guide wire 31 is curved downward so that the extreme point of the finger is nearly opposite to the middle of the first glass rod 21 as shown in Figure 1. When in place this finger is slightly spaced from 25 the end face of the plate 15 so as to permit the insertion of the yarn or thread. This finger or guide 31 makes it almost impossible for the yarn to whip or balloon out of the device as the shuttle is picked across the loom. 30 It will be seen that my construction provides a very simple and readily adjusted tensioning device and I have found in actual practice that by allowing the yarn to pass through a tensioner having smooth glass 35 elements that I secure a much evener and smoother tension of the yarn than where the yarn passes over metallic elements, and that the action of these glass surfaces is to stop all kinks in the yarn and secure finer cloth. If one of the rods is by any chance 40 broken it can be easily replaced and thus the device will last almost indefinitely. The yarn at no time with my device touches any part of the metal and no matter what 45 kind of yarn is used it will not cut into the metal and cause the yarn to break. The guide 31, as before stated, makes it almost impossible for the yarn to whip or balloon out of the shuttle as the shuttle is 50 picked and, as before explained, the tensioning device is adjustable for coarser or finer yarns.

While the embodiment of my invention which I have illustrated has been found 55 thoroughly effective in actual practice, I do not wish to be limited thereto as it is obvious that it might be varied in many ways without departing from the spirit of the invention.

60 This construction provides for the shifting of the two tension or friction members toward or from each other, which was accomplished in my prior patent by screws passing laterally through the side walls of the 65 shuttle. In my prior patent, however, these

screws, which were disposed in recesses in the side walls of the shuttle, I found in practice were liable to come out and were liable to cut the reed. Therefore, I provide the single set screw extending through the 70 bottom of the shuttle disposed in the recess therein and whereby the two members may be adjusted toward or from each other, this construction also permitting relatively 75 small tension members to be mounted in the shuttle, which the prior described construction did not do.

I claim:

1. In a shuttle having a shuttle cavity, means for tensioning yarn comprising oppositely disposed yarn-engaging members, each having a series of vertically disposed, alternately protuberant and depressed portions, the protuberant portions of one member being disposed opposite the depressed portions of the other member and the protuberant portions of both members intersecting a common vertical plane extending longitudinally through the shuttle, one of said members bearing against the side wall 90 of the cavity and against the bottom thereof and having an effective width equal to the width of the cavity, means clamping the last named member to the shuttle, and means adjustably engaging the other of said 95 thread-engaging members with the first named member and permitting the adjustment of the second named member toward and from the first named member.

2. In a shuttle having a cavity, means for tensioning yarn comprising oppositely disposed yarn-engaging members, each having a vertical series of alternately protuberant and depressed portions, the protuberant portions of one member being disposed opposite the depressed portions of the other member and said protuberant portions of both members intersecting a common vertical plane extending longitudinally through the shuttle, one of said members having a laterally extending flange, the base of the member formed by said flange having a width equal to the width of the shuttle cavity, the other of said members resting upon the upper face of the flange of the 110 first named member and adjustable toward and from the first named member, and means whereby the second named member may be held in its adjusted position upon and relative to the first named member. 115

3. In a shuttle having a shuttle cavity, yarn-tensioning means comprising confronting members disposed within said cavity, each member having a series of vertical, alternately protuberant and depressed yarn-engaging portions, the protuberant portions of one member being disposed opposite the depressed portions of the other member and said protuberant portions of the two members intersecting a common plane, one of 125 130

5 said members having a base fitting the shuttle cavity between the side walls thereof and having a transversely extending passage and a transversely extending slot, a bolt 50
5 passing transversely through the shuttle and through said passage and holding the first named member in place, and a headed screw passing through the other member and engaging said slot whereby the last 55
10 named member may be held in adjusted relation to the first named member.

4. In a shuttle, yarn tensioning means 15 comprising oppositely disposed members, a plurality of vitreous rods mounted upon each member and spaced to each other, the rods of one member being disposed opposite the spaces between the rods of the other member, one of said members having a base 20 flange formed with a transversely extending slot, a bolt passing transversely through this base flange and through the wall of the shuttle and the other member having a downwardly extending headed screw, the shank of which is adapted to be disposed in said 25 slot, whereby said last named member may be adjusted and held in adjusted position with relation to the first named member.

5. In a shuttle having a cavity, yarn-tensioning means comprising opposing 30 tensioning members, one of said members being formed with a laterally extending base flange fitting said cavity between the side walls thereof, means extending transversely through the shuttle and transversely through said base flange whereby 35 the member may be held and engaged with the wall of the shuttle, the other member resting upon the upper face of said base flange, and a fastening device passing through the base of the second named member and through the slot of the first named member whereby the second named member 40 may be adjusted and held in adjusted position with relation to the first named member. 45

6. As an article of manufacture, yarn-tensioning means for shuttles comprising opposed coating members, said members having on their confronting faces a series of vertically disposed alternate protuberant 50 and depressed portions, the depressed portion of one member coming opposite to a protuberant portion of the other member, one of said members having a laterally extending flange adapted to fit within the 55 cavity of a shuttle and having a transverse bore adapted to receive a bolt passing through the shuttle whereby said member may be held in place within the shuttle cavity, the other member having a double 60 headed screw engaging the transverse slot and being adapted to rest upon said flange and being adjustable on the flange toward or from the first named member, the screw acting to hold the second named member 65 in its adjusted position.

7. As an article of manufacture, yarn tensioning means for shuttles comprising opposed members, said members carrying upon their confronting faces vertically disposed vitreous rods, one of said members having a laterally extending flange having a transversely extending slot, a bolt passing transversely through said flange whereby the member may be engaged with the 70 wall of the shuttle, the other member being adapted to rest upon said flange and having a downwardly extending screw extending through said slot, the screw having a head whereby the screw may be turned in 75 binding engagement with the wall of the slot to thereby hold the members in adjusted relation, the last named member at its entrance end carrying a downwardly and laterally extending finger beneath 80 which the thread is adapted to pass.

In testimony whereof I hereunto affix my signature.

ARTHUR MELLOR.
